UNITED STATES PATENT OFFICE.

JOHN H. SCHOTT, OF BOULDER, COLORADO.

PULLING-MACHINE.

1,186,849.

Specification of Letters Patent. Patented June 13, 1916.

Application filed August 5, 1915. Serial No. 43,854.

To all whom it may concern:

Be it known that I, JOHN H. SCHOTT, a citizen of the United States, residing at Boulder, in the county of Boulder and State 5 of Colorado, have invented certain new and useful Improvements in Pulling-Machines; and I do declare the following to be a full, clear, and exact description of the invention, such as will enable others skilled in 10 the art to which it appertains to make and use the same:

My invention relates to improvements in pulling devices, and more particularly to those designed primarily for the stretching 15 of wire, cables, and the like.

The object of the invention is to provide a machine of the class specified which although being simple and inexpensive, will be highly efficient and durable, and will 20 possess a number of advantageous features, among the most salient of which is the provision of means whereby should breakage of the wire occur, injury to the operator will be prevented.

25 With this general object in view, the invention resides in certain novel features of construction and in unique combinations of parts to be hereinafter fully described and claimed, the descriptive matter being supplemented by the accompanying drawings 30 wherein:

Figure 1 is a side elevation of the invention applied to use, with the carriage member thereof at the beginning of its working 35 stroke; Fig. 2 is a similar view after one working stroke has been completed; Fig. 3 is an elevation of the opposite side of the machine with parts broken away and in section; Fig. 4 is a top plan view; Fig. 5 is 40 a horizontal longitudinal section taken on the plane designated by the line 5—5 of Fig. 1; Fig. 6 is a vertical transverse section taken on the plane of the line 6—6 of Fig. 1; Fig. 7 is a similar view viewed on 45 the plane indicated by the line 7—7 of Fig. 1.

In these drawings which constitute a part of the application, and in which similar reference characters designate corresponding parts throughout the several views, the 50 numeral 1 indicates broadly a channel-shaped guide member which is formed of an elongated rectangular back plate 2 and a pair of parallel laterally projecting flanges 55 3 preferably though not necessarily formed integrally with the edge portions thereof

and extending in the same direction therefrom, one end of the back plate 2 and the adjacent ends of the flanges 3, being shown as formed integrally with a hook 4, by 60 means of which, through the instrumentality of a chain or the like 5, the device may be anchored to a post as disclosed in Fig. 1, or may be secured to another appropriate type of anchor. 65

The inner facing sides of the flanges 3 are provided with longitudinal grooves 6 receiving slidably therein, tongues 7 on the opposite edges of an elongated carriage plate 8, such plate having on one end an ear 70 9 to which is pivoted the offset end of a pitman 10, the other end of said pitman being mounted on an eccentric wrist pin 11 carried by a disk 12 which is rotatably mounted in the guide member 1 adjacent the hook 4 75 thereof.

The disk 12 is carried by a shaft 13 which extends through the back plate 2 into a gear box 14 and carries a comparatively large gear 15 meshing with the driving 80 pinion 16, the gear and pinion being both disposed in the gear box. For driving the pinion 16, an appropriate crank 17 is provided, such crank being positioned adjacent the back of the plate 2, for a reason to be 85 explained as the description proceeds.

Secured by screws or the like to one edge portion of the carriage plate 8, on the front side thereof, is one or more fixed jaw members 18 having gripping teeth on one face 90 with which the toothed pulling dogs 19 coact, such dogs 19 being pivoted to the opposite edge portion of the plate 8 by removable screws 20 and being forced normally toward the jaws 18 by appropriate springs 21. 95

Rigidly secured by screws or the like to the inner side of one of the flanges 3, is one or more rigid jaw members 18^a having serrated faces alined with such faces of the members 18, while pivoted upon removable 100 screws 20^a to ears 22 on the inner side of the opposite flange 3, is one or more toothed holding dogs 19^a which are forced normally toward the jaw members 18^a by appropriate springs.

In operation, when the machine is to be used for stretching wire or the like, the hook 4 is connected by means of the chain 5 or an equivalent device with a post or other appropriate anchor, whereupon the wire to 110 be stretched is positioned between the dogs 19 and 19^a and the jaw members 18 and 18^a.

Rotation of the crank 7, will now reciprocate the carriage plate 8, thus causing the dogs 19 and jaws 18 to move therewith, the result being that such devices will travel rearwardly upon the wire when the latter is held by dogs 19^a and jaws 18^a, during the rearward movement of the carriage plate, but when said plate moves forwardly, the wire will be gripped by the members 18 and 19 and will thus be pulled forwardly between the dogs 19^a and the jaws 18^a, the last named members now serving to again grip the wire while the pulling means again moves rearwardly previously to another working stroke.

As above suggested, the machine may be constructed with but one dog 19 and one dog 19^a, in which case but one member 18 and one member 18^a will be employed, this construction being capable of use for a number of purposes, although the two sets of dogs are preferably employed when the machine is to be used as a wire stretcher, since in case barbed wire is being stretched, if one of the dogs 19 or 19^a engages a barb and cannot therefore be effective, the other dog will contact with the body portion of the wire and will thus reliably grip the same.

It is to be observed that the crank 17 is disposed adjacent the closed side of the channel-shaped guide 1, this being a rather important feature of the invention, since in case of breakage of the wire, due for instance to a defect therein, the hand of the operator will be shielded and thus injury will be prevented. All working parts of the machine are protected either by disposition in the channel-shaped guide 1 or by the gear box 14, whereby such parts may be protected to a great extent against injury due

to rough usage, and all movable parts are detachably secured in place, whereby new members may be substituted for those which may become so worn as to render them ineffective. In addition to these advantages, attention is directed to the fact that the face plate of the gear box 14 may be removed, whereupon gears of different ratios may be substituted for the gears 15 and 16 shown in the drawings. By so doing, the speed of the machine as well as the power thereof may be varied at will.

In the drawings, certain specific details of construction have been shown for accomplishing probably the best results, and in the preceding such details have been described, but it is obvious that I need not be restricted thereto otherwise than to the extent to which the appended claim limits me.

I claim:

A pulling machine comprising a channel-shaped guide having on the exterior of its closed side a gear box, a reciprocatory carriage confined in said guide, a crank likewise confined therein but spaced from the carriage, a pitman connecting the crank and the carriage, a shaft extending from the crank into the gear box, a gear on said shaft confined in the gear box, an additional gear meshing with the aforesaid gear and likewise confined in the gear box, a hand crank for rotating said additional gear, and independent gripping devices carried by the guide and by the carriage.

In testimony whereof I have hereunto set my hand in presence of two subscribing witnesses.

JOHN H. SCHOTT.
